UNITED STATES PATENT OFFICE

94,329

DESIGN FOR A COMBINED AUTOMOBILE, BOAT, AND AIRPLANE

George Brown, Chicago, Ill.

Application May 23, 1934, Serial No. 51,894

Term of patent 7 years

To all whom it may concern:

Be it known that I, George Brown, a citizen of the United States, residing at Chicago, in the county of Cook and State of Illinois, have invented a new, original, and ornamental Design for a Combined Automobile, Boat, and Airplane, of which the following is a specification, reference being had to the accompanying drawing, forming a part thereof.

Figure 1 is a top plan view showing my new design;

Figure 2 is a side elevational view showing my new design; and

Fig. 3 is a top plan view showing my design having the wing elements in the extended position, and shown to a somewhat reduced scale.

I claim:

The ornamental design for a combined automobile, boat, and airplane, substantially as shown.

GEORGE BROWN.
